PAGE 4

Fig. 4

Fig. 1 is a perspective view of an embossing machine showing our new design;

Fig. 2 is a top plan view thereof;

Fig. 3 is a side elevational view thereof looking in the direction of the arrows 3—3 on Fig. 2;

Fig. 4 is a side elevational view thereof looking in the direction of the arrows 4—4 on Fig. 2; and

Fig. 5 is a front elevational view of the embossing machine.

We claim:

The ornamental design for an embossing machine, substantially as shown.
